US00D966772S

(12) **United States Design Patent** (10) **Patent No.:** **US D966,772 S**
(45) **Date of Patent:** **** Oct. 18, 2022**

(54) **INSTANT WARMER**

(71) Applicant: **Ningbo Huiyoo Baby Products Co., Ltd**, Cixi (CN)

(72) Inventor: **Meirong Gong**, Cixi (CN)

(**) Term: **15 Years**

(21) Appl. No.: **29/811,399**

(22) Filed: **Oct. 14, 2021**

(51) LOC (13) Cl. **07-01**

(52) U.S. Cl.

USPC **D7/313**; D7/311

(57) **CLAIM**

The ornamental design for an instant warmer, as shown and described.

DESCRIPTION

FIG. 1 is a front and top perspective view of an instant warmer, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the instant warmer that form no part of the claimed design.

1 Claim, 8 Drawing Sheets
